HOT WATER DEFLECTOR FOR A COFFEE URN

John C. Martin and Eugene G. Rescho, Springfield, Ill.,
assignors to Bunn-O-Matic Corporation, Springfield,
Ill.

Filed Aug. 14, 1970, Ser. No. 24,502

Term of patent 14 years

Int. Cl. D7—04

U.S. Cl. D44—26

FIG. 1 is a top plan view of a hot water deflector for a coffee urn embodying our new design;

FIG. 2 is a bottom plan view;

FIG. 3 is a perspective view; and

FIG. 4 is a vertical sectional view taken along line 4—4 of FIG. 1 looking in the direction of the arrows.

We claim:

The ornamental design for a hot water deflector for a coffee urn, substantially as shown.
